UNITED STATES PATENT OFFICE.

JOHN ARTHUR FRANCIS, OF PARKERTON, WYOMING.

RIPPER FOR WELL CASINGS.

Application filed November 3, 1924. Serial No. 747,662.

To all whom it may concern:

Be it known that I, JOHN ARTHUR FRANCIS, a citizen of the United States, and a resident of Parkerton, county of 5 Converse, and State of Wyoming, have invented a new and useful Improvement in Rippers for Well Casings, of which the following is a full, clear, and exact description.

My invention relates to improvements in 10 devices for ripping well casings, so as to render the removal of the casing comparatively easy, and it consists in the combinations, constructions, and arrangements herein described and claimed.

15 It often happens that the casings of wells, such as oil wells, become fastened in the hole, so that it cannot be removed from the hole, except by parting it from the place where it is fast.

20 An object of my invention is to provide a device which may be inserted within the casing and which, by the use of the ordinary well drilling machinery, such as jars and the like, will cut the joint which is fast, 25 thus permitting the casing to be removed.

A further object of my invention is to provide a device of the type described, which is relatively simple in construction but positive in action.

30 Other objects and advantages will appear in the following specification, and the novel features of the invention will be particularly pointed out in the appended claims.

My invention is illustrated in the accompanying drawings, forming part of this application, in which

Figure 1 is a side view of the casing ripper, certain parts being shown in section for the sake of clearness,

40 Figure 2 is a view of the casing ripper in operative position in a well casing, this view being at right angles to Figure 1,

45 Figure 3 is a fragmentary sectional view showing the position of the cutters in the casing ripper as it enters the casing, and

Figure 4 is a similar view showing the position of the parts after the cut has been completed.

50 In carrying out my invention, I provide a body portion 1, having a tapered screw 2 at the end thereof arranged to be secured to the bottom member of a set of jars of ordinary construction. The body portion 1 has an integral reduced extension 3 which 55 bears at its end a head 4. The latter is provided with a tapered threaded recess 5

communicating with a cylindrical recess 6 at the end thereof. On opposite sides of the reduced portion 3 are leaf springs 7, which are held by means of screw bolts 8, 30 or in any other suitable manner.

The cutter block consists of two portions 9 and 10, as shown in Figure 1. These portions, when secured together, have a tapered threaded extension 11 which is held 65 at one end by a bolt 12. A bolt 13 at the opposite end of the portions 9 and 10 also secures them together. The portions 9 and 10 have registering slots to form a recess 14. In this recess are disposed the cutter 70 blades 15. As will be seen from the drawings, these cutter blades are provided with laterally extending trunnions 16 which enter bores 17 by means of which they are journalled. Within the recess 14 are springs 75 18 which are mounted on pins 19, secured to the body portion of one of the cutter block segments, such as that shown at 9. One end of each of these springs bears on the top of the block, the other end being 80 designed to bear on the cutter blades when the latter are in certain positions, as will be explained later.

From the foregoing description of the various parts of the device, the operation 85 thereof may be readily understood. Let us assume that a casing has been caught in the hole, so that it cannot be removed. The cause of this lies largely in the coupling or collar which secures the sections of the casing together, since this is of larger diameter than the casing. Often it is possible to tell just what joint is causing the trouble. In such instance, the collar ripper at the bottom 90 of the jars is lowered, together with the usual apparatus, i. e., the jars, the stem and the rope socket. In Figure 3, I have shown the position of the cutter blades 15 while the collar ripper is being lowered. It will be noted that they are pressed upon by the 95 springs 18, so as to hold them against the sides of the casing during the downward movement. This downward movement is continued until the cutter blades pass the suspected collar, and then the tools are 100 raised. When the cutter blades clear the end of the casing section 20 (see Figure 2) they enter the recess 21 between the ends of the casing sections 20 and 22, which are connected together by the collar 23, so that the 105 cutter is then in the position shown in Figure 2. In order to hold the cutters in position,

tion, or rather to prevent their swinging downwardly, I provide the pins 24, which may be made of soft metal, such as a wire nail, and which will suffice for maintaining the cutters in position until the cutting operation actually begins.

After the cutters have entered the recess 21, the jars are operated. The ordinary set of jars, as is well known, consists of 10 links, so that if the collar ripper is held stationary, as it is in the present instance, by means of the frictional contact of the leaf spring 7 on the sides of the casing, the desired movement of the upper jar will be permitted, but on the upward movement it will cause a jerk which will drive the cutter into 15 the end of the casing 22. At each reciprocation of the jars, the cutter is further advanced so that eventually it reaches the 20 position shown in Figure 4. Thus it will be seen that there are two vertical slots cut in the end of the casing so as to weaken the joint. Now when force is applied, the casing will separate at this point.

25 It will be understood that after the cutters are in operative position, such as that shown in Figure 2, the action of the jars will cause the shearing of the pins 24, thus permitting the cutters to swing outwardly into the position shown in Figure 4 to cut through the casing. When the casing ripper is withdrawn, the cutter blades will swing downwardly to the dotted line position shown in 30 Figure 4, thus permitting the easy withdrawal of the tool.

I claim:

1. A casing ripper comprising a body portion, spring means carried on the opposite sides of said body portion and adapted to 40 frictionally engage the interior of a well casing when the casing ripper is lowered, a cutter block composed of two sections, means for securing the sections together, means for

securing the united sections to the body portion of the casing ripper, a pair of oppositely extending pivotally mounted cutter blades carried by said cutter block, spring means for normally pressing the cutter blades outwardly, pins for limiting the pivotal movement of the cutter blades while the 45 blades are being brought to operative position, said pins being subsequently sheared by the cutter blades during the cutting operation, whereby a further pivotal movement of the blades is permitted.

2. A casing ripper comprising a body portion having a tapered threaded recess, a cutter block composed of two sections adapted to be secured together and having contiguous portions constituting an extension 50 and threaded to enter the threaded recess in the socket, said sections having registering recesses constituting a slot, and registering bores, and cutter blades disposed in said slot and having trunnions arranged to enter 55 said bores.

3. A casing ripper comprising a body portion having a tapered threaded recess, a cutter block composed of two sections adapted to be secured together and having contiguous portions constituting an extension 70 and threaded to enter the threaded recess in the socket, said sections having registering recesses constituting a slot, registering bores, cutter blades disposed in said slot and 75 having trunnions arranged to enter said bores, and pins carried by one of said sections and arranged to project normally within said slot for limiting the pivotal movement of the cutter blades while said 80 blades are being brought to operative position, said pins being subsequently sheared by the cutter blades during the cutting operation, whereby a further pivotal movement of the blades is permitted.

JOHN ARTHUR FRANCIS
